UNITED STATES PATENT OFFICE.

DAVID F. CURTIN, OF CHICAGO, ILLINOIS.

CUP OR CONTAINER.

1,260,520.

Specification of Letters Patent. Patented Mar. 26, 1918.

Application filed June 28, 1915. Serial No. 36,769.

To all whom it may concern:

Be it known that I, DAVID F. CURTIN, a citizen of the United States, residing at Chicago, in the county of Cook and State of Illinois, have invented certain new and useful Improvements in Cups or Containers, of which the following is a description.

My invention relates to cups or receptacles formed of light flexible material adapted to fit within and be supported by a suitably formed holder when in service.

The object of my invention is to produce a simple and convenient cup of the kind described which may be formed of paper or other suitable inexpensive material and which may be packed or nested together for shipment or storage thus permitting their convenient renewals at a comparatively low cost.

20 To this end my invention consists in the novel construction, arrangement and combination of parts herein shown and described and more particularly pointed out in the claims.

25 In the accompanying drawings wherein like or similar reference characters indicate like or corresponding parts:

Figure 1 is a suitable blank for forming a cup embodying my invention.

30 Fig. 2 is an elevation of my improved cup.

Fig. 3 is an enlarged section taken substantially on line 3—3 of Fig. 2 showing the thickness of the walls and the waterproof coating greatly exaggerated.

35 Fig. 4 is a view of a conveniently shaped blank adapted to be attached to the wall of the cup for forming a slight lateral projection on the wall of the cup.

In the form shown the blank 1 for making 40 my improved cup, comprises a segment formed of suitable material having a curved edge 2 and two converging straight edges 3 and 4 with a projection 5 provided near their proximate ends. The straight edge is substantially radial to the curved edge 2 while 45 the straight edge 4 preferably extends to the edge 2 on a line tangent to the curved edge of the projection 4. The length of the side 2 and the angle inclined between the sides 50 3 and 4 obviously depends upon the desired diameter and depth of the cup.

In the preferred form the blank 1 is coated upon one side with paraffin or other suitable adhesive water-proof material 6 and in bending the form the coating 6 is arranged at the exterior of the cup so that the

coating upon the material cannot under any circumstances become mixed with the contents of the cup or be scraped off when using a spoon or other utensil in the cup.

60

Any suitable material may be employed upon my blank for rendering the same impervious to water or other fluid and also for connecting the overlapping portions of the blank 1 and permanently securing them together.

65

In the preferred form a suitable mixture of paraffin and other material is employed for this purpose and the blank is bent to form the cup when the water proofing material is slightly warmed so as to readily adhere when portions of the blank are brought together and thus secure an absolutely tight joint where the edges of the blank overlap and the chilling of material permanently attaches the parts together.

75

The several parts are so formed and constructed that the material forming the projection 5 wraps around the apex of the cup reinforcing the same at this point and also tending to form a more secure fastening between the overlapped edges of the blank.

80

When thus constructed it is obvious that where several of these cups are "nested" that is, packed one inside of the other, the walls of the several cups will be in close contact with each other and the coating 6 may tend to stick the adjacent cups together especially, when slightly warmed. To avoid this difficulty a piece 7 of any suitable material,

85

preferably the same as the cup, is wrapped upon the exterior of the cup to form a projection and slightly space the walls of the adjacent cups from each other when so nested.

90

In the preferred construction a disk 7 of suitable size formed of uncoated material similar to that employed for forming the blank 1 is provided and placed in contact with the coated exterior of the cup and extending across the junction of the edges of the blank 1 so as to reinforce this connection

95

and provide an uncoated projection upon the exterior of the cup adapted to contact with the uncoated interior of the next adjacent cup thus preventing the possibility of adhesion between them, at the same time preventing the overlapping portions of the blanks from becoming disengaged.

100

It is obvious that the form of the part 7 as well as the form or construction of the blank for forming my improved cup may be changed as desired from that shown in the drawing

105

and that various other immaterial modifi-

110

cations may be made in my device without departing from the spirit of my invention, hence I do not wish to be understood as limiting myself to the exact form or construction shown.

What I claim as new and desire to secure by Letters Patent is:

1. In a cup, converging side walls adapted to snugly nest with a similar cup, a coating of waterproof material on one side of said wall and an uncoated projection upon said side wall adapted to engage the wall of a similar cup and prevent the walls of two cups from contacting when the cups are placed one within the other.
2. In a cup, converging side walls adapted to snugly nest with a similar cup, a coating of waterproof material upon the exterior of said side wall and an uncoated projection upon the outside of said side wall adapted to engage the wall of a similar cup and prevent the walls of two cups from contacting when the cups are placed one within the other.
3. In a cup, converging side walls comprising a flat paper blank having a liquid proof coating on one side and bent to the desired form and having the edges attached to the body of said blank, said cup being adapted to snugly nest with a similar cup, a flat paper part attached to the side of said cup intermediate its height and overlapping the edge of said blank thereby forming a projection upon said side wall adapted to engage the wall of a similar cup and prevent the walls of two cups from contacting when the cups are placed one within the other.
4. In a cup, converging side walls comprising a flat paper blank bent to the de-

sired form and having the edges attached to the body of said blank adapted to snugly nest with a similar cup, an uncoated projection upon said side wall comprising a piece formed of a material similar to said cup permanently attached thereto at the junction of one edge of said blank with the side wall adapted to engage the wall of a similar cup and prevent the walls of two cups from contacting when the cups are placed one within the other.

5. In a cup, converging side walls comprising a flat paper blank bent to the desired form and having the edges attached to the body of said blank adapted to snugly nest with a similar cup a coating of adhesive waterproof material on the outside of said wall, an uncoated projection upon the outside of said side wall comprising a piece formed of a material similar to said cup permanently attached thereto adapted to engage the wall of a similar cup and prevent the walls of two cups from contacting when the cups are placed one within the other.

6. As an article of manufacture, a conical cup formed of a plurality of adhering superposed convolutions of a piece of paper coated with water-proof adhesive, such cup having a wrapper with a non-adhesive outer surface secured to the exterior of the apex portion of the cup.

In testimony whereof, I have hereunto signed my name in the presence of two subscribing witnesses.

DAVID F. CURTIN.
